UNITED STATES PATENT OFFICE.

FRANK G. SHELAIN, OF ROCKFORD, ILLINOIS, ASSIGNOR TO NELSON KNITTING COMPANY, OF ROCKFORD, ILLINOIS, A CORPORATION OF ILLINOIS.

KNITTING MACHINE.

Application filed December 15, 1924. Serial No. 755,816.

This invention relates to straight knitting machines having either single or parallel rows of needles and in which a pattern cylinder or the equivalent controls at least one row of needles. In the present application I have illustrated my invention in connection with a straight parallel row knitting machine of the kind in which a single pattern cylinder has been employed in prior machines to control only one row of needles for fashioning, as for example, for knitting the toe and heel of a sock or stocking.

One of the purposes of the present invention is to provide mechanism whereby the needles of both the front and rear rows are controlled by a single pattern cylinder. To this end I have in the present embodiment of my invention provided mechanism associated with the pattern cylinder and operated independently of or supplemental to rotative movement of said cylinder for controlling the needles of either or both rows in addition to the usual cylinder control, whereby to produce a greater variety of fabrics and patterns than was possible with prior machines of this kind.

The present invention is, moreover, an improvement in knitting machines of the type disclosed in the Nelson Patents Nos. 214,308 dated April 15, 1879 and 576,881 dated February 9, 1897. The improvement consists generally stated in the provision of mechanism for controlling the front as well as the rear needles, this mechanism in the present embodiment acting in conjunction with the pattern cylinder for imparting needle control movements while the cylinder is at rest and supplemental to the control motion of the cylinder itself, as will be described more fully hereinafter.

Another purpose of my invention is to provide novel mechanism for knitting a mock rib or rib-like fabric as distinguished from a plain fabric. By the use of this mechanism I am enabled to produce a greater variety of fabrics, patterns and designs than was heretofore possible with machines of this kind. For example, heretofore it was customary to knit the foot and leg of a sock or stocking entirely of plain knitting on a machine of the kind referred to and to knit a rib top on a circular machine and then join the two fabrics together on a looper or by sewing or any suitable method.

According to my invention I secure sub-

stantially the same effect, that is, a rib top sock or stocking having a foot and leg portion of plain knitting and a top portion of mock rib or rib-like knitting, but the top portion is knit directly onto the leg portion. The entire sock or stocking is thus knit as of a single operation and comprises a one-piece rib fabric which is more durable than a two-piece fabric united by sewing, looping or otherwise. All of the advantages of a full rib fabric are obtained and, in addition, the mock rib fabric is more elastic than the ordinary rib fabric and the union between them is stronger. This is especially desirable in the knitting of hosiery; and my invention is not confined to the use of this mechanism for knitting the top portion, but instead, it may be employed to knit any determined part of the sock or stocking. It follows that a greater variety of designs may be produced in the leg or any portion of a sock or stocking; whereas heretofore with machines of this kind only one bed of needles was controlled, making it impossible to produce a uniform design or fabric by round and round knitting.

A further purpose of my invention is to provide improved mechanism for controlling the jack-levers of both front and rear rows of needles, especially in machines employing only a single pattern cylinder designed only for controlling one row of needles.

Still another purpose is to provide mechanism of the character described which may be applied as an attachment to machines of the Nelson type or to any employing a pattern cylinder.

Other objects and attendant advantages will be appreciated by those skilled in this art as the invention becomes better understood by reference to the following description when considered in connection with the accompanying drawings, in which—

Figure 1, is a front, fragmentary elevation of a knitting machine embodying my invention;

Fig. 2, is an end elevation of the machine looking at the left end thereof, that is, at the end remote from the driving mechanism;

Fig. 3, is a fragmentary vertical section through the needle bed and pattern cylinder taken substantially on the line 3—3 of Fig. 1, illustrating the needle control;

Figs. 4 and 5, are similar sections show-

ing different movements of the needle control;

5 Fig. 6, is a somewhat diagrammatic or development view of the control mechanism within the pattern cylinder, looking outwardly as on the line 6—6 of Fig. 3;

10 Figs. 7, 8, 9, 11, 13, 15 and 17 are diagrammatic views of the front and rear needles, showing different positions thereof;

15 Figs. 10, 12, 14 and 16, are detail views showing the four initial control movements described later; and

Fig. 18, shows a sock produced by the present mechanism.

20 In disclosing and describing this invention I have for purpose of clarity shown in the drawings only such parts of a knitting machine as are necessary for an understanding of the invention, and reference may be had to the above-mentioned Nelson patents and to others in this art for a more complete description and disclosure of this particular type of knitting machine. It should be understood however that my invention in its broader aspect is not confined to this particular application, but is applicable to other knitting machines.

25 For convenience in description and in accordance with the understanding in this art, 30 that side of the machine at which the work is discharged, namely the right side viewing Fig. 3, is called the "front" and the other the "rear" side and, viewing Fig. 1, the end on the left is termed the "left" end of the machine and the opposite the "right", throughout this specification.

35 Referring more particularly to the drawings, the main frame 21 carries upright side plates 22 and 23 which in turn support the front and rear needle beds 24 and 25 respectively. Each needle bed is suitably constructed for supporting in spaced relation a row of needles, the front and rear needles being indicated by 26 and 27 respectively. 40 Each needle is adapted to be advanced or projected upwardly from the full line position shown in Fig. 3 to the dotted line position in which to take the yarn from the yarn carrier designated generally by 28, shown 45 in Fig. 2, and to be retracted to draw the yarn through the previous loop on the needle and thus form a stitch. Each needle is in the present instance advanced and retracted by similar movements of a jack, the jacks for 50 the front and rear needles being indicated by 29 and 31 respectively. The needles of each bed are advanced and retracted by means of a cam slide designated generally by 32 having cams which act on an upstanding lug 33 on each needle jack. Each needle jack 31 is controlled by a jack-lever 34 to raise and lower its lug 33 into and out of 55 operative relation to its needle actuating cam, whereby to place its needle in or out of action as the case may be, as is well under-

stood in this art. The jack-levers 34 are in turn controlled by a pattern cylinder designated generally by 35, each jack lever being pivoted at 36 and having projections 37 and 38 which bear against the 60 pattern cylinder and are controlled by the cam grooves therein. The front needles 26 are thrown into and out of action by mechanism (not shown) for raising and lowering the needle actuating cam as explained in said Patent No. 214,308. The cam slides and yarn carrier are reciprocated in unison by mechanism (not shown) which is driven from a main drive shaft 39 (Fig. 1). This shaft is connected by 65 spur gears 41 to a shaft 42 to which is fixed a cam gear 43 which operates a star pinion 44 in turn fixed to a shaft 45. This shaft has a fixed pinion 46 meshing with a gear 47 on the pattern cylinder. By means of 70 this driving train the pattern cylinder and needle actuating cams are operated in timed relation. The construction and operation of the foregoing parts are fully described in the Nelson patents above-mentioned and it 75 is accordingly believed that a more detailed description is not necessary for an understanding of the present invention.

80 In a machine of the character described it has been customary to knit the usual heel and toe with the rear needles controlled by the pattern cylinder, during which operation the front needles are held down out of action, the front needles being brought into action only during round and round knitting 85 through the foot, ankle and leg portions. According to my invention I propose to control both the front and rear needles by mechanism auxiliary or supplemental to but acting in conjunction with the pattern cylinder for the purpose of producing a variety 90 of fabrics, patterns and designs. In the particular example herein disclosed, each alternate needle of both the front and rear beds is held out of action during each alternate 95 round of knitting, with the result that a mock rib or rib-like fabric is produced. In other words the fabric comprises a course 100 knit forward and back on all of the front and rear needles respectively and a course knit forward and back with each alternate 105 needle in the front and rear rows respectively, these courses being repeated to knit 110 a tubular fabric of the desired length.

115 In the preferred embodiment of my invention the mechanism for controlling the needle jacks is carried in part by the pattern cylinder 35 and is in turn controlled from a controller cam designated generally by 48 120 coaxial and fixed with respect to the pinion shaft 45. This controller cam is therefore rotated in timed relation to the needle actuating cams and its present location is advantageous because it promotes simplicity 125 and practicability. This controller cam is 130

adapted to actuate one or more motion trains leading to the needle jacks and operating in part through or in connection with the pattern cylinder. In the preferred embodiment a single motion train is employed for the needle jacks for the front and rear needles respectively, which will be separately described.

Referring first to the motion train leading to the rear needle jacks and more particularly to the jack-levers 34 therefor, reference may be had to Figs. 3 and 6 which clearly show the construction. Motion is transmitted to this train of parts by the controller cam 48 acting against a pin or plunger 49 slidably mounted in the peripheral wall of the pattern cylinder in a plane substantially radial with respect thereto. The controller cam is cut away at three peripherally spaced points providing equally spaced high and low cam portions 51 and 52 respectively. The pin 49 projects beyond the cylinder and is adapted to bear against the periphery of the controller cam and to move lengthwise in its support in the cylinder wall by following the high and low portions of the cam. Said pin 49 at its inner end is connected to a lever 53 pivotally mounted at 54 on the inner peripheral wall of the cylinder. The lever 53 at its end remote from the pin 49 is pivotally connected to one end of a rectangular frame composed of end members 55 and 56 and pin-carrying members 57 and 58. The end members 55 and 56 are pivotally supported intermediate their ends on a shaft 50, in turn suitably supported on the inner peripheral wall of the pattern cylinder. The pin-carrying members 57 and 58 are pivotally attached at their ends through the intermediary of links 59 to the ends of the end members 55 and 56. The frame members 57 and 58 each carry a series of pins 61 which extend outwardly through holes in the cylinder wall and are adapted to be projected and withdrawn by rocking the frame on the shaft 59 through movement of the lever 53 imparted by the controller cam. The pins 61 are so positioned as to be in registration with the projections 37 and 38 on alternate jack-levers 34 for the purpose of rocking said jack-levers when the cylinder is at rest in a control movement simulating the cam action of the pattern cylinder effected by rotative movement thereof. It will be manifest from the foregoing that a motion train is provided between the controller cam and certain jack-levers for the rear needles whereby certain of said needles may be thrown into and out of action by operation of the controller cam. Referring to Fig. 3 it will be noted that when the controller cam is rotated in a counter-clockwise direction the pin will be moved inwardly by the first cam portion 51 thereby

tilting the rectangular frame above-described so as to withdraw one set of fingers 61 and project the other and thereby rock the alternate jack-levers 34 in a clockwise direction to lower the jack lugs 33. This leaves 70 the remaining alternate jack-levers undisturbed with their respective jacks in position to be operated by the needle actuating cam. Upon continued movement of the controller cam in the same direction the next 75 following depression 52 will be brought into alignment with the pin 49, allowing the latter to be forced outwardly and the entire motion train moved in the reverse direction to reverse the position of the pins 61, this 80 movement being imparted by one or more springs 62 in this case attached to the inner wall of the cylinder and bearing outwardly against the pin-carrying member 58. It will also be noted that inasmuch as the 85 motion train just described is carried by the pattern cylinder and has a motion transmitting part at a single point thereon, it will be brought into operative position or relation to the controller cam only once 90 during a complete revolution of the cylinder. However when this point in the knitting is reached the cylinder remains abreast until a given number of courses have been knit as determined by a suitable counting 95 device. In the present case this is effected by cutting away several teeth in the cylinder gear 47 at a given point so that the pinion 46 will turn idly and by providing a single tooth 63 (Fig. 1) on the shaft 45 which 100 actuates a gear segment 64 which in turn moves the pattern cylinder after a determined number of courses during which the controller cam functions to control certain 105 needles of the rear row as just described and similar needles of the front row as will be presently described, this being done while the cylinder is at rest. It will be further noted that the pinion 46 and consequently 110 the controller cam 48 is actuated at the end of each stroke forward and backward of the cam slides, this being effected through the driving train above-described including the star pinion 44 which has six equally spaced teeth, also that the controller cam 115 is rotated one-twelfth of a revolution at each actuation of the shaft 45. The particular effect of this control motion will be better understood from a description of the general operation which will follow later 120 and after a description of the second motion train operated by the controller.

The second motion train for the purpose of controlling certain front needles is actuated by a pin or plunger 65 slidably mounted in the pattern cylinder wall in juxtaposition to the pin 49 and in such angular relation thereto as to bear against the controller cam 48 and be operated thereby. The pin 125 65 connects within the cylinder to a lever 130

66 pivotally attached at 60 to the cylinder. The lever is inclined lengthwise of the cylinder (Fig. 6) so that its end 67 is disposed beyond the end of the cylinder remote from the driving mechanism. A suitable flat spring 68 interposed between the cylinder and the lever 66 urges the latter in a direction to move the pin 65 outwardly against the controller cam. Suitable means such as pins 69 fixed to the cylinder hold the extended end 67 of the lever from displacement. The lever 66 is adapted to operate the remaining part of the second motion train which leads to a series of jack-levers 71, one for each alternate front needle jack 29. These jack levers, pivotally mounted at 72 and each shaped to receive the rear end of a jack, are connected together by a rod 73 for swinging them downwardly and upwardly from the position shown in Fig. 3 to move the jack lugs 33 out of and into operative relation to the needle actuating cam, thus throwing alternate front needles out of and into action, respectively. The needle bed 24 is grooved deeper at its lower end as at 74 for each jack 29 that is lowered. A plurality of flat springs 75 attached at one end to the bed 24 engage at the opposite end beneath the rod 73 and constantly urge the jack-levers upwardly. The jack-levers are adapted to be lowered as a unit by downward movement of a pair of arms 76 engaged over the rod 73 and fixedly connected to a rock shaft 77 mounted in brackets 78 attached to the under side of the bed 24. Said rock shaft has a forwardly turned arm 79 pivotally connected by a link 81 to a lever 82 which is pivoted at 83 on the side plate 22 and has an extended end 84 equipped with a shoe or striking plate 85 located in the path of the lever end 67 and adapted to be actuated thereby. From the foregoing it will be manifest that when the pin 65 and the lever end 67 are brought into cooperative relation to the controller cam and shoe 85 respectively, motion may be transmitted by the controller cam to the jack levers 71 through operation of the second motion train just described. Thus when the pin 65 is moved inwardly from the position shown in Fig. 3 by rotative movement of the controller cam in a counter-clockwise direction the lever 66 will be rocked to move the shoe 85 outwardly and thereby rock the shaft 77 in a clockwise direction and lower the jack-levers 71 to throw the alternate front needles out of action. Outward movement of the pin 65 when it enters a low portion 52 of the controller cam allows the springs 75 to raise the jack levers 71.

The operation of my improvements for knitting a plain sock with a mock rib top as shown in Fig. 17 will now be described. The knitting is started with the rear needles only which knit the toe 86 in the usual man-

ner as controlled by the pattern cylinder. The foot portion 87 is then knit by both the front and rear needles in round and round plain knitting. Following this the front needles are held out of action and the heel 88 is knit by the rear needles. The front needles are again brought into action and the leg portion 89 is knit by both front and rear needles in round and round knitting. This is the customary way of knitting a plain sock on a machine of the Nelson type. When the point 91 is reached the needle controlling mechanism carried by the pattern cylinder will be brought into operative relation to the controller cam for the purpose of knitting the mock rib fabric above-referred to, indicated in Fig. 18 by the top 92.

In order to clearly illustrate the operation of the controller cam with respect to the needles I have shown a series of diagrammatic views, Figs. 7 to 17 inclusive. These views are not intended to show the actual number of needles employed but are intended merely for purpose of illustrating the movement of the needles in and out of action. Figs. 7 and 8 illustrate a single course of circular knitting comprising the forward stroke to the left in which all of the front needles 26, shown advanced to take the yarn, are in action and will be drawn down in the knitting stroke as the yarn carrier and cam slides move to the left. During this stroke and following the retraction of the front needles the rear needles will be advanced as shown in Fig. 8. This course is completed by the back stroke to the right in which all of the rear needles knit, leaving the front needles advanced as shown in Fig. 9. At the end of this back stroke the pattern cylinder will be brought to the position for the first controller cam movement and will remain in this position during and until a mock rib fabric of the desired length has been knit, as referred to above. The first controller movement at the point indicated by the numeral "one" in a circle, Fig. 9, is shown in Figs. 4 and 10, consisting in moving the pin 49 outwardly to throw the alternate rear needles out of action in the manner described above. On the next forward stroke all of the front needles are knit as shown in Fig. 9, but during this stroke only the alternate rear needles will be advanced, as shown in Fig. 11. At the end of this stroke the second controller movement takes place, indicated by the numeral "two" (Fig. 11), consisting in a rotative movement of one-twelfth of a revolution in a counter-clockwise direction from the position shown in Fig. 10 to that in Fig. 12. By this operation the pin 65 is moved outwardly by the high portion 51 of the controller cam, thus throwing the alternate front needles out of action in the man-

ner described above. The pin 49 is undisturbed by the second controller movement which, therefore, holds the alternate needles of both the front and rear rows out of action. On the next stroke (back) the alternate rear needles shown advanced in Fig. 11 will knit and during this back stroke the alternate front needles will be advanced as shown in Fig. 13. At the end of this back stroke the third controller movement takes place, denoted by "three" and shown in Figs. 5 and 15, wherein the controller cam has moved one-twelfth of a revolution and allowed the pin 49 to enter the next succeeding low portion 52 to return all of the rear needles into action and has held the pin 65 in the position with the alternate front needles out of action. On the next stroke to the left, that is, the forward stroke 20 the alternate front needles held advanced as shown in Fig. 13 are knit and all of the rear needles will be advanced as shown in Fig. 15. At the end of this forward stroke the cam controller will be actuated in its fourth controller movement, denoted by "four" and shown in Fig. 16, in which the pin 65 enters the low portion 52 of the cam and restores all of the front needles to action. On the next stroke to the right, that 30 is, on the back stroke all of the rear needles which are advanced as shown in Fig. 15 will knit, and all of the front needles will be advanced, as shown in Fig. 17. At the end of this back stroke the next succeeding high portion 51 of the controller cam will 35 remove the pin 49 inwardly, thus performing the first controller movement, described above with reference to Figs. 9 and 10. This knitting operation will then be repeated until a tubular fabric of the desired 40 length has knit, whereupon the pattern cylinder will be advanced to render inoperative the needle control mechanism just described.

It will be noted that the fabric produced 45 under control of the controller cam 48 comprises alternate courses in which all of the front and rear needles are in action and intermediate courses in which alternate needles of the front and rear rows are in action. This leaves alternate wales of continuous stitches and intervening wales of alternate stitches which produces a rib-like fabric. This fabric is more elastic than a plain fabric and is therefore very desirable 50 for the top of a sock or stocking. Furthermore in the particular example described the sock is knit in one piece and its strength is not impaired at the juncture of the leg and top portions 89 and 92 as is the case 55 when these portions are knit separately and sewed or otherwise united.

It should be further noted that my invention is in no way limited to the knitting of the top portion only of a sock or stocking, 60 but that it might be applied for knitting any

portion of the tubular fabric. For example, the controller cam 48 may be put into operation at the end of the heel 88 or at any point thereafter for knitting the remainder of the fabric. By the use of different colored yarns 70 for the front and rear needles various and distinctive designs may be produced. Furthermore by equipping the pattern cylinder with an additional lever and cam operated pin similar to the lever 66 and pin 65 but 75 located at a proper position on the cylinder the front needles may be controlled before the heel 88 is reached, whereby to knit the upper portion 93 of the foot according to a pattern or design similar to the leg portion 80 89. In other words I also propose the use of plural auxiliary control mechanisms of the character described for both the front and rear needles, located at any desired positions on the cylinder. 85

It will thus be seen that my invention contemplates arranging the supplemental or auxiliary needle control mechanism to knit a wide variety of fabrics and that the present disclosure is for purpose of illustration. 90 It should also be understood that my invention is not to be confined to the details of construction shown herein, but that it is capable of application in various ways and by the use of equivalent devices, to any 95 straight knitting machine.

I claim as my invention:

1. In a straight knitting machine, in combination, a bed of needles, jacks, jack-levers, a pattern cylinder, means for imparting rotative movement to the cylinder, and means carried by the cylinder adapted to be brought into cooperation with the jack-levers and operated by said cylinder-rotating means supplemental to the cylinder movement for changing the position of said jack-levers. 100

2. In a straight knitting machine, in combination, a row of needles, jacks, jack-levers, a pattern cylinder, and mechanism mounted 110 within the cylinder for moving the jack-levers back and forth.

3. In a straight knitting machine, in combination, a row of needles, jacks, jack-levers, a pattern cylinder, a needle-actuating cam, a controller operated in time relation to the needle-actuating cam, and mechanism carried by the cylinder and operated by said controller to move certain jack-levers. 115

4. In a straight knitting machine, in combination, a row of needles, jacks, jack-levers, a pattern cylinder, a needle-actuating cam, a controller operated in timed relation to the needle-actuating cam, and mechanism carried by the cylinder and operated by said controller to move certain jack-levers, said mechanism being carried within the cylinder and including jack-lever-operating and controller-operated elements projecting outwardly through the cylinder and adapted to 120 125 130

- be brought into cooperation with the jack-levers and controller by rotation of the cylinder.
5. In a straight parallel row knitting machine, in combination with the needles, jacks, needle-actuating cams, and pattern mechanism for one row of needles, of a controller operated in timed relation to the cams, and mechanism operated by the controller supplemental to the action of said pattern mechanism for controlling the jacks of both rows of needles to put alternate needles of each row out of action at alternate rounds of knitting.
10. In a straight parallel row knitting machine, in combination with the needles, jacks, needle-actuating cams, and pattern cylinder, of a controller operated in time relation to the cams, and mechanism including jack operating means carried by the cylinder and operated at determined times by said controller when said cylinder is at rest for controlling the jacks of both rows of needles to put alternate needles of each row out of action at alternate rounds of knitting.
15. In a straight parallel row knitting machine, in combination with the needles, jacks, needle-actuating cams, and pattern cylinder, of a controller operated in time relation to the cams, and mechanism including jack operating means carried by the cylinder and operated at determined times by said controller when said cylinder is at rest for controlling the jacks of both rows of needles to put alternate needles of each row out of action at alternate rounds of knitting.
20. In a Nelson type straight knitting machine, in combination with the front and rear rows of needles and the pattern cylinder for controlling the rear needles through the intermediary of jacks, of control means for rotating the cylinder, and mechanism operated by said control means for operating both the front and rear needle jacks.
25. In combination with the front and rear rows of needles of a straight parallel row knitting machine, of a pattern cylinder for controlling the rear needles through the intermediary of jacks, control means for rotating the cylinder, and mechanism operated by said control means for operating both the front and rear needle jacks; said mechanism including motion-transmitting elements connected with the front and rear needle jacks and means carried by the cylinder and adapted to be operated by the control means when brought into cooperative relation to said elements and means.
30. In a straight parallel row knitting machine of the character described, the combination with the pattern cylinder operating pinion, of a controller cam on said pinion, and means carried by the cylinder operated by the controller cam for rendering certain needles operative and inoperative.
35. In a straight parallel row knitting machine of the character described, the combination with the pattern cylinder operating pinion, of a controller cam on said pinion, and means carried by the cylinder operated by the controller cam for rendering certain needles operative and inoperative at determined times.
40. In a straight parallel row knitting machine of the character described, the combination with the pattern cylinder operating pinion, of a controller cam on said pinion, and means carried by the cylinder operated by the controller cam for rendering certain needles operative and inoperative at determined times.
45. In a straight parallel row knitting machine of the character described, the combination with the pattern cylinder operating pinion, of a controller cam on said pinion, and means carried by the cylinder operated by the controller cam for rendering certain needles operative and inoperative.
50. In a straight parallel row knitting machine of the character described, the combination with the pattern cylinder operating pinion, of a controller cam on said pinion, and means carried by the cylinder operated by the controller cam for rendering certain needles operative and inoperative.
55. In a straight parallel row knitting machine of the character described, the combination with the pattern cylinder operating pinion, of a controller cam on said pinion, and means carried by the cylinder operated by the controller cam for rendering certain needles operative and inoperative at determined times.
60. In a straight parallel row knitting machine of the character described, the combination with the pattern cylinder operating pinion, of a controller cam on said pinion, and means carried by the cylinder operated by the controller cam for rendering certain needles of both the front and rear rows operative and inoperative at determined times.
65. In a straight parallel row knitting machine of the character described, the combination with the pattern cylinder operating pinion, of a controller cam on said pinion, and means carried by the cylinder operated by the controller cam for rendering certain needles of both the front and rear rows operative and inoperative at determined times.
70. In a straight parallel row knitting machine of the character described, the combination with the pattern cylinder operating pinion, of a controller cam on said pinion, and means carried by the cylinder operated by the controller cam for rendering certain needles of the rear row operative and inoperative to the action of their needle-operating cam.
75. In a straight parallel row knitting machine of the character described, the combination with the pattern cylinder operating pinion, of a controller cam on said pinion, and a motion-train carried by the cylinder and adapted to be operated by said controller cam to render certain needles of the front row operative and inoperative to the action of their needle actuating cam.
80. In a straight knitting machine, in combination, a row of needles, jacks, jack-levers, a pattern cylinder, and means carried within the cylinder including radially movable means to shift certain of said jack-levers.
85. In a straight knitting machine, in combination, front and rear rows of needles, jacks, jack-levers, and means carried within the cylinder including radially movable elements to shift certain jack-levers of needles in both said front and rear rows.
90. In a straight knitting machine, in combination, a row of needles, jacks, jack-levers, a pattern cylinder, a cylinder operating pinion, a controller cam on said pinion, and a motion-transmitting train carried within and by the cylinder including a part extending through the cylinder wall and adapted to be operated by said controller cam and a series of parts extending through the cylinder wall and adapted to transmit motion to certain jack-levers.
95. In a straight knitting machine, in combination, a row of needles, jacks, jack-levers, a pattern cylinder, a cylinder operating pinion, a controller cam on said pinion, and a motion-transmitting train carried within and by the cylinder including a part extending through the cylinder wall and adapted to be operated by said controller cam and two rows of parts extending through the cylinder wall and adapted to be brought into registration with certain jack-levers at opposite sides of their pivot axes whereby to shift said levers back and forth.
100. In a straight knitting machine having a front and a rear row of needles, a pattern cylinder for controlling only the rear needles and a pinion for imparting rotative movement to the cylinder, of a controller cam on said pinion, and means operated by said controller cam and acting through the cylinder for controlling needles in the front row.
105. In a straight knitting machine having a front and a rear row of needles, a pattern cylinder for controlling only the rear needles and a pinion for imparting rotating movement to the cylinder, of a controller cam on said pinion, and means operated by said controller cam.
110. In a straight knitting machine having a front and a rear row of needles, a pattern cylinder for controlling only the rear needles and a pinion for imparting rotating movement to the cylinder, of a controller cam on said pinion, and means operated by said controller cam.
115. In a straight knitting machine having a front and a rear row of needles, a pattern cylinder for controlling only the rear needles and a pinion for imparting rotating movement to the cylinder, of a controller cam on said pinion, and means operated by said controller cam.
120. In a straight knitting machine having a front and a rear row of needles, a pattern cylinder for controlling only the rear needles and a pinion for imparting rotating movement to the cylinder, of a controller cam on said pinion, and means operated by said controller cam.
125. In a straight knitting machine having a front and a rear row of needles, a pattern cylinder for controlling only the rear needles and a pinion for imparting rotating movement to the cylinder, of a controller cam on said pinion, and means operated by said controller cam.

controller cam for controlling needles of both the front and rear rows.

19. In a straight knitting machine having a front and a rear row of needles, a pattern cylinder for controlling only the rear needles and a pinion for imparting rotating movement to the cylinder, of a controller cam on said pinion, and means operated by said controller cam acting through independent motion trains for controlling needles of both the front and rear rows.

20. In a straight knitting machine, in combination, front and rear rows of needles, a pattern cylinder, a cylinder operating pinion, a controller cam on said pinion, and means operated by said controller cam acting through independent motion-trains to respectively control the operation of needles in the front and rear rows.

21. In a straight knitting machine, in combination, front and rear rows of needles, a pattern cylinder, cylinder-operating means, a controller cam operated by said means, and means operated by said controller cam acting through independent motion-trains to respectively control the operation of needles in the front and rear rows.

22. The combination with a straight knitting machine having a front and a rear row of needles and a pattern cylinder for controlling only the rear needles through the agency of cam surfaces on the cylinder acting against jack-levers, of supplemental means on the cylinder acting when the latter is at rest to impart control movements to the jack-levers of both the front and rear rows of needles.

23. In a straight knitting machine, in combination, a row of needles, jacks, jack-levers, a pattern cylinder adapted by rotative movement to actuate the jack levers, and supplemental means on the pattern cylinder operative when it is at rest for moving certain of the jack levers to control certain needles in action supplemental to the rotative control action of the pattern cylinder.

24. In a straight knitting machine, in combination with front and rear rows of needles, jacks, a pattern cylinder for controlling the jacks of only one row, and means on the pattern cylinder acting supplemental to the rotative movement thereof to control jacks of both the front and rear rows of needles.

25. In a straight knitting machine having a front and rear row of needles, needle-operating cams, jacks movable into and out of operative relation to said cams for bringing the needles into and out of action, a pattern cylinder for actuating certain of

the jacks, and means on the pattern cylinder operating when the latter is at rest to move certain of the jacks of both the front and rear rows into and out of operative position.

26. In a straight row knitting machine, in combination, a front and a rear row of needles, means for advancing and retracting the needles, means for controlling the needles in action including a pattern cylinder, means for imparting step-by-step movement to the pattern cylinder, and means operated by the last mentioned means for acting supplemental to the cylinder action to bring needles in both beds into and out of operative relation to their respective advancing and retracting means.

27. In a straight knitting machine of the Nelson type, in combination with the front and rear rows of needles and mechanism for operating them to knit a sock the leg portion of which is of plain knitting, of means operating when the pattern cylinder is at rest for holding each alternate needle of each bed out of action when knitting the top portion of the sock, whereby to produce a rib-like top fabric as distinguished from a plain knit top fabric.

28. In a straight knitting machine, in combination, a front and a rear row of needles, a pattern cylinder for controlling only one row of needles, and pattern control mechanism operating when the pattern cylinder is at rest for controlling both rows of needles.

29. In a straight knitting machine, in combination, a front and a rear row of needles, a pattern mechanism operating in step-by-step movements to control one row of needles, and additional pattern mechanism operating when the first mentioned pattern mechanism is at rest for controlling both rows of needles.

30. In a parallel row knitting machine in combination, a single pattern cylinder for controlling the needles of one row only, and supplemental pattern mechanism acting through said pattern cylinder when the latter is at rest to control the needles of both beds in alternation to produce a tubular mock rib fabric.

31. In a straight parallel row knitting machine in combination, a single pattern cylinder for controlling the needles of only one row to produce fashioning, as when knitting a heel, and pattern mechanism in addition to said pattern cylinder for controlling the needles of both beds to produce tubular mock rib knitting.
